UNITED STATES PATENT OFFICE

FERNAND E. D'HUMY, OF SCARSDALE, NEW YORK, ASSIGNOR TO RAMP BUILDINGS CORPORATION, OF NEW YORK, N. Y., A CORPORATION OF DELAWARE

BUILDING

Application filed April 30, 1930. Serial No. 448,555.

This invention relates to storage buildings and more particularly to garages of the type having storage floors located at different levels and connected by ramps over which the 5 automobiles may be driven under their own power from floor to floor to reach their respective storage spaces. Important objects of the invention are to provide for the construction of such a garage from previously fabricated parts adapted to be conveyed to the building site and readily set up there to form the structure; to provide such a garage whose storage capacity may be readily varied according to the requirements of its 10 patronage; and to provide a knock down garage structure capable of being readily taken down, removed in parts to another site and erected again.

In the drawings,

20 Fig. 1 is a vertical section through the building taken on the line 1—1 of Fig. 3, upon a larger scale than the latter;

Fig. 2 a view similar to Fig. 1 taken on the line 2—2 of Fig. 1;

25 Fig. 3 a section taken on the line 3—3 of Fig. 2;

Fig. 4 a side view of the building;

30 Fig. 5 a diagrammatic view indicating the manner in which a number of panels are associated to form individual storage compartments in the building;

Fig. 6 a fragmentary, horizontal section taken on the line 6—6 of Fig. 1, upon a larger scale;

35 Fig. 7 a vertical section taken on the line 7—7 of Fig. 6;

Fig. 8 a perspective view of a number of the compartment-forming panels separated;

40 Fig. 9 a vertical section taken on the line 9—9 of Fig. 1, upon a larger scale;

Fig. 10 a detail, vertical section taken on the line 10—10 of Fig. 7;

Fig. 11 a detail, horizontal section taken on the line 11—11 of Fig. 7;

45 Fig. 12 a detail, vertical section taken on the line 12—12 of Fig. 6;

Fig. 13 a detail, vertical section taken on the line 13—13 of Fig. 3;

50 Fig. 14 a detail, vertical section taken on the line 14—14 of Fig. 9;

Fig. 15 a horizontal sectional view of the garage structure provided with heat insulating means;

Fig. 16 a vertical section taken on the line 16—16 of Fig. 15; and

Fig. 17 a sectional view upon a larger scale taken through one of the compartment panels and a heat insulating panel attached thereto.

The present garage building, in the arrangement of its floors and ramps, is of the 60 type disclosed in my U. S. Patent No. 1,298,183, issued March 25, 1919. Therein, two groups of superposed storage and driveway floors, at staggered levels, are disposed at opposite sides of a vertical division plane 65 and are joined by two groups of oppositely inclined ramps spaced along said plane. My present invention provides for the construction of such a garage from fabricated parts, such as panels preferably formed of sheet 70 metal. Certain panels form individual storage compartments and also the outer walls of the building; other panels form driveway floors along said compartments; still other panels form ramps connecting the driveway 75 floors; and all of said panels are releasably connected together to form a strong structure.

The panels forming the individual storage compartments are assembled upon the building site to form four straight parallel banks 80 of compartments. These banks are designated 1, 2, 3 and 4. In each bank the compartments are disposed side by side in superposed horizontal rows. Banks 1 and 2 are upon 85 the same level and are spaced apart to define a corridor space into which the compartments thereof open. Banks 3 and 4 are similarly disposed with relation to each other but are supported at a staggered level with relation 90 to banks 1 and 2 and with the compartments of the staggered banks 2 and 3 disposed back to back along a vertical division plane at the center of the building. Preferably the vertical offset or stagger between the banks is 95 equal to one half a story, or one half the height of a compartment.

In forming the compartments, side panels 5, end panels 6, and top and bottom panels 7 are employed. In each bank adjacent side 100

by side compartments have a common side panel 5 and adjacent superposed compartments have a common panel 7 which forms the top of one and the bottom of the other, as indicated in Fig. 5. The back to back compartments of the staggered banks 2 and 3 also have common end panels 6 therebetween. Along the corners of each compartment the panels are removably or releasably joined together. In the present instance the panels are shown as secured to angle irons 8 by means of bolts 9. Other suitable joining means may be employed, however. Each compartment built up from the panels is preferably of a size and shape to accommodate an automobile and provide sufficient clearance around it. However, it may be made large enough to accommodate several automobiles.

At two points spaced along the central division plane of the building the staggered compartment banks 2 and 3 have several vertical rows of compartments omitted to form gaps or transverse corridor spaces connecting the two longitudinal corridor spaces between the banks. Mounted in the latter corridor spaces are superposed driveway floors 10 and 11 extending along the length of said spaces and leading to all of the compartments therealong. Disposed in the said transverse corridor spaces are two groups of superposed ramps 12 and 13. Ramps 12 lead upward in succession from the driveway floors 10 to the adjacent staggered driveway floors 11 while the ramps 13 are oppositely inclined and lead from floors 11 to floors 10, so that the floors and ramps form a substantially spiral path for automobile traffic to and from the compartments at all levels.

Each of the driveway floors is preferably formed of a series of panels 14 extending across the corridor space. At its opposite ends each panel 14 is removably supported by the compartment structures which it transversely connects and is substantially the width of a compartment. In the present instance the forward edges of the compartment panels 7 carry beams 15 forming ledges upon which the ends of the floor panels rest and are removably secured by bolts 16. Each ramp is also preferably formed of a series of transverse panels 17 extending across the transverse corridor spaces and removably bolted as at 18 to supporting beams 19. The latter are removably bolted as at 20, to the adjacent compartment panels 5 of the banks 2 and 3. At the ends of the ramps the latter and their connecting driveway floors are removably bolted as at 21 to supporting beams 22 extending across the gaps in the banks 2 and 3 and removably supported in any suitable manner by the compartment structures of said banks.

In the set up structure just described the end panels 6 of the compartments and the outermost side panels 5 form the outer side

walls of the building except for the ends of the longitudinal corridor spaces. The latter are closed by panels 23 removably secured in any suitable manner to the compartment structures at opposite sides of the corridor spaces. Also, the topmost panels 7 and the topmost ramps 12 and 13 combine to form a roof structure for the building. One of the lowermost side panels 23 is formed with a doorway 24 opening into the lowermost driveway floor 10 and forming an entrance and exit for the automobile traffic.

My invention provides a very desirable set-up and take-down garage structure. The various compartment, floor and ramp panels will be made preferably in standard sizes and may be ordered from a manufacturer in the required number and conveniently transported in a flat, compact form to the building site. Without extensive excavation or other preparation they may be readily set up on a vacant lot or field. The erection may be only tentative and the proprietor may at first set up only a modest number of compartments. Upon an increase of patronage beyond the capacity of the garage the proprietor may easily enlarge the latter either vertically or laterally by erecting more compartments and by adding to the driveway floors and ramps. The various panels are all designed for this convenient build up. If, on the other hand, the location of the garage should prove to be a bad one, or it should be required to vacate the land, the garage may be readily knocked down, transported to another location and again set up.

The various panels forming the compartments, the driveway floors, the ramps and the building walls are all preferably made of sheet metal reinforced by any suitable means. There are six species of panels in the building structure namely, the compartment side panels 5, the compartment top and bottom panels 7, the floor panels 14, the ramp panels 17 and the closure panels 23. The panels of each species are all similarly formed and are interchangeable.

In order to retain heat in the garage building during cold weather and also to shield it from the heat of the sun during hot weather the outermost panels of the building may be provided with heat insulating means, as shown in Figs. 15 to 17 inclusive. Here each outermost panel has its outer face covered by an independently fabricated heat insulating panel, each outermost compartment side panel 5 having an insulating panel 5^a, each compartment end panel 6 having an insulating panel 6^a, each uppermost compartment panel 7 having an insulating panel 7^a, each uppermost panel 14 bearing an insulating panel 14^a, each uppermost ramp panel 17 having an insulating panel 17^a and each corridor closing panel 23 having a panel 23^a. The structure of each insulating panel in

the present instance comprises a sheet 25 of celotex, cork or other suitable insulating material enclosed by sheet metal 26. The panel so formed is of the same shape and size as the panel which it covers, or substantially so, and is detachably secured thereto by bolts 27. All of the main panels are preferably provided with bolt apertures for the attachment of the insulation panels so that any of the main panels may be used in the outermost positions when erecting the building. When the insulating panels are all applied in the erected building they form continuous side walls.

While I have shown and described a very desirable form of my invention I do not wish to be limited strictly to this disclosure but reserve the right to make such changes as will lie within the scope of the claims.

What I claim is:

1. A multi-story cellular garage structure comprising two units closely arranged with their inner vertical walls forming the center line of the structure, each unit embodying two parallel sets of super-imposed steel storage compartments opening inwardly into a space between said sets each horizontal row of compartments forming one story of the structure, and the horizontal and vertical walls of the compartments forming the horizontal floors and the vertical internal and external structural members of the garage; horizontal structures extending across the space between said two sets of compartments and tying the two sets together and forming a driveway for each story of each unit; and transverse structural members extending across the center line of the garage structure and connecting the driveways of one unit with the driveways of the other unit to rigidly secure the two units together, said transverse members serving as cross-connecting driveways.

2. A multi-story cellular garage structure comprising two units closely arranged with their inner vertical walls forming the center line of the structure, each unit embodying two parallel sets of super-imposed steel storage compartments opening inwardly into a space between said sets each horizontal row of compartments forming one story of the structure, and the horizontal and vertical walls of the compartments forming the horizontal floors and the vertical internal and external structural members of the garage; horizontal steel panel structures extending across the space between said two sets of compartments and tying the two sets together and forming a driveway for each story of each unit; and transverse steel panel structural members extending across the center line of the garage structure and connecting the steel panels of the driveways of one unit with the steel panels of the driveways of the other unit to rigidly secure the two units to-

gether, said transverse steel panel members serving as cross-connecting driveways.

3. A multi-story cellular garage structure comprising two units closely arranged on different levels to stagger the floors with their inner vertical walls forming the center line of the structure, each unit embodying two parallel sets of super-imposed steel storage compartments opening inwardly into a space between said sets each horizontal row of compartments forming one story of the structure, and the horizontal and vertical walls of the compartments forming the horizontal floors and the vertical internal and external structural members of the garage; horizontal structures extending across the space between said two sets of compartments and tying the two sets together and forming a driveway for each story of each unit; and inclined transverse structural members extending across the center line of the garage structure, each of said inclined structural members connecting the driveway of one unit with the next lower driveway of the other unit to rigidly secure the two units together, said inclined transverse members serving as cross-connecting floor-to-floor driveways.

4. A multi-story cellular garage structure comprising two units closely arranged on different levels to stagger the floors with their inner vertical walls forming the center line of the structure, each unit embodying two parallel sets of super-imposed steel storage compartments opening inwardly into a space between said sets each horizontal row of compartments forming one story of the structure, and the horizontal and vertical walls of the compartments forming the horizontal floors and the vertical internal and external structural members of the garage; horizontal structures extending across the space between said two sets of compartments and tying the two sets together and forming a driveway for each story of each unit; and two pairs of oppositely inclined transverse structural members extending across the center line of the garage structure, each of said inclined structural members connecting the driveway of one unit with the next lower driveway of the other unit to rigidly secure the two units together, said inclined transverse members serving as cross-connecting floor-to-floor driveways.

5. A multi-story cellular garage structure comprising two units closely arranged on different levels to stagger the floors with their inner vertical walls abutting together, each unit embodying a plurality of sets of super-imposed steel storage compartments opening inwardly into a space between said sets each horizontal row of compartments forming one story of the structure, and the horizontal and vertical walls of the compartments forming the horizontal floors and the vertical internal and external structural members of

the garage; horizontal steel panel structures extending across the space between said two sets of compartments and tying the two sets together and forming a driveway for each 5 story of each unit; and two pairs of oppositely inclined transverse steel panel structural members extending across the line between the units, each of said inclined structural members connecting the driveway of one 10 unit with the next lower driveway of the other unit to rigidly secure the two units together, said inclined transverse members serving as cross-connecting floor-to-floor driveways.

15 6. A multi-story cellular garage structure comprising two units closely arranged with their inner vertical walls abutting together, each unit embodying a plurality of parallel sets of super-imposed steel storage compartments opening inwardly into a space between said sets each horizontal row of compartments forming one story of the structure, and the horizontal and vertical walls of the compartments forming the horizontal floors and 20 the vertical internal and external structural members of the garage; horizontal structures extending across the space between said two sets of compartments and tying the two sets together and forming a driveway for each 25 story of each unit; and transverse structural members extending across the line between the inner vertical walls of the garage structure and connecting the driveways of one unit with the driveways of the other unit to rigidly 30 secure the two units together, said transverse members serving as cross-connecting driveways.

35 7. A multi-story cellular garage structure comprising two units closely arranged with 40 their inner vertical walls abutting together, each unit embodying a plurality of parallel sets of super-imposed steel storage compartments opening inwardly into a space between said sets each horizontal row of compartments 45 forming one story of the structure, and the horizontal and vertical walls of the compartments forming the horizontal floors and the vertical internal and external structural members of the garage; horizontal steel panel 50 structures extending across the space between said two sets of compartments and tying the two sets together and forming a driveway for each story of each unit; and transverse steel panel structural members extending across 55 the line between the inner vertical walls of the garage structure and connecting the driveways of one unit with the driveways of the other unit to rigidly secure the two units together, said transverse members serving as 60 cross-connecting driveways.

In testimony whereof I hereunto affix my signature.

FERNAND E. D'HUMY.
